(57) **CLAIM**

The ornamental design for a label printer, as shown and described.

DESCRIPTION

FIG. 1 is a front and top perspective view of a label printer showing our new design;

FIG. 2 is a right end perspective view thereof;

FIG. 3 is a top and side perspective view thereof; and,

FIG. 4 is a right side elevation thereof.

The broken lines shown in the drawings illustrate environmental structure and form no part of the claimed design.
